UNITED STATES PATENT OFFICE.

RUDOLPH J. J. MUELLER, OF SHEBOYGAN, WISCONSIN, ASSIGNOR TO UNIVERSAL OXYGEN COMPANY, OF SHEBOYGAN, WISCONSIN, A CORPORATION OF WISCONSIN.

CHEESE-HOOP.

1,343,402.

Specification of Letters Patent. Patented June 15, 1920.

Application filed January 7, 1918. Serial No. 210,621.

To all whom it may concern:

Be it known that I, RUDOLPH J. J. MUELLER, a citizen of the United States, residing at Sheboygan, in the county of Sheboygan and State of Wisconsin, have invented certain new and useful Improvements in Cheese-Hoops, of which the following is a specification, reference being had to the accompanying drawing, forming a part thereof.

This invention relates more particularly to metal cheese hoops of the kind shown and described in my application Serial No. 21,600, filed April 15, 1915.

The main objects of the present invention are to so reinforce the mouth or open end of the hoop as to avoid cracking, distorting and bruising the hoop in removing a cheese therefrom by striking the inverted hoop forcibly downward upon a table or block according to the common practice, so that a bandage ring or sleeve and follower or another hoop, will not fit into it and the hoop will not stand the pressure and hard usage to which it is subjected; and generally to improve the construction and operation of hoops of this class.

It consists in certain peculiarities of construction as hereinafter particularly described and pointed out in the claims.

In the accompanying drawing like characters designate the same parts in the several figures.

Figure 1 is an axial section indicated by the line 1—1, Fig. 2, of a complete metal cheese hoop embodying the invention, and a portion of another hoop inserted therein and illustrating the manner of assembling the hoops in a press; Fig. 2 is a cross section on the line 2—2, Fig. 1; Fig. 3 is a plan view of a follower of the preferred construction for use with hoops of the kind shown; and Fig. 4 is a fragmentary view, in section, of the upper end of the hoop, showing in exaggerated form the flaring of that end and the non-corrosive metal closure at the joint between the body of the hoop and reinforcing band.

The hoop, which is made of heavy sheet metal, comprises a tapering body or lower section *a*, and a cylindrical upper section or extension *b*. The tapering body section *a* is provided at its smaller end with a fixed perforated bottom *c*. The cylindrical section or extension *b* is joined at one end to

the larger end of the body section *a*, forming therewith an internal shoulder or seat *d* for a split bandage sleeve or ring *e*, with which the hoop is provided and which is removably fitted in said cylindrical section or extension, and is of greater width so as to project above the hoop when it is inserted therein with its lower edge against the shoulder or seat *d*. The upper or outer end of the ring or sleeve *e* is flared outwardly to facilitate entering a follower therein. The thickness of the metal of which the ring or sleeve *e* is made, corresponds with the width of the shoulder or seat *d*, so that when the ring or sleeve is inserted in a hoop, as shown in Fig. 1, its internal diameter corresponds with the internal diameter of the body section *a* at its larger end, and when a number of hoops are assembled with bandage rings or sleeves and with followers for pressing the curd contained in the hoops into cheese, the follower will pass freely from the bandage rings or sleeves into the larger ends of the body sections *a*.

Each hoop is provided on opposite sides with handles *f*, preferably made of plain flat metal bands bent to the desired shape and welded at the ends to opposite sides of the body section *a* so as to form strong tight joints therewith which can be easily kept clean.

Each hoop is also provided between the bottom *c* and handles *f* with a bearing ring or shoulder *g*, preferably formed as shown, of a concave band of sheet metal, seam welded at the edges to the body section *a* of the hoop so as to form therewith strong closed joints without cracks or crevices in which dirt can lodge. This ring or shoulder by engagement with the upper or outer end of the bandage ring or sleeve *e* of an adjoining hoop, serves as a stop to limit the extent to which one hoop can be inserted into another, as shown in Fig. 1.

The several sections and parts of which the hoop is composed are preferably joined together by autogenous seam welding so as to form in effect an integral structure without open joints or crevices in which dirt can lodge and with plain smooth surfaces which can be easily kept in a clean and sanitary condition.

The hoop is provided with a follower *h*, preferably formed as shown, in one piece, of heavy sheet metal, with a slightly down-

turned rim *i* to stiffen it and give it a slightly concave or dishing shape on the under side, which tends to crowd the curd or cheese toward the center of the hoop and prevent it from being squeezed out between its edge and the surrounding bandage ring or sleeve *e*, or body section *a* of the hoop.

The follower is also formed with drainage holes *j* and with isolated bosses or projections *k*, pressed upwardly or outwardly therefrom and adapted by engagement with the perforated bottom of an adjoining hoop to maintain a drainage space between the follower and contiguous hoop bottom *c*.

15 The follower is formed with one or more bosses *l*, through which holes *m* are formed for the insertion of a hook or hooks for removing the follower from a hoop without disfiguring the cheese against which the follower is pressed.

The hoop, bandage sleeve and follower are tinned or plated with noncorrosive metal, which will not injure or affect the cheese and which is easily kept clean.

20 25 In removing cheese from a hoop of this kind, it is customary to sharply strike the open end of the hoop in an inverted position on a table or block.

To stiffen and strengthen the mouth or open end of the hoop and enable it to withstand the impact of the blows to which it is subjected in removing the cheese therefrom, the edge of the upper cylindrical section *b* is folded down flat against the outside of the section, thereby forming a reinforcing band *n*, having a rounded rim, which gives the mouth of the hoop a slightly flaring form and facilitates the insertion of the bandage ring or sleeve *e* therein.

The tin or other noncorrosive metal plating or coating applied to the hoop, fills or closes the seam between the down-folded edge and the body of section *b*, thereby avoiding any crack or crevice in which dirt can collect.

45 50 55 The reinforcing band *n* preserves the proper shape of the hoop, thereby facilitating the insertion and removal of the bandage ring or sleeve *e*, and prevents the blows to which the hoop is subjected in removing cheese therefrom from breaking or cracking and thereby weakening it so that it will not withstand the pressure to which it is subjected in a press.

I claim:

1. A metal cheese hoop having the edge at its open end folded outwardly, downwardly and flatly against the body and forming a reinforcing band with a rounded rim giving the hoop a flaring mouth, the hoop being coated with noncorrosive metal which closes the joint between the body and downwardly folded edge.

2. A sheet metal cheese hoop comprising a body having a cylindrical section forming therewith an internal shoulder for a bandage sleeve, the open end of the cylindrical section having its edge folded down flat against the outside of said section into a reinforcing band which gives the hoop a rounded rim and flaring mouth, the hoop being coated with noncorrosive metal which closes the joint between the downwardly folded edge and outside of said section.

65 70 75 In witness whereof I hereto affix my signature.

RUDOLPH J. J. MUELLER.
